ENDLESS BUFFING AND POLISHING BELT

Harry E. Welker, Anderson, Ind., assignor to General Motors Corporation, Detroit, Mich., a corporation of Delaware

Application June 21, 1957, Serial No. 667,154

7 Claims. (Cl. 51—188)

This invention relates to the buffing and polishing art and particularly to buffing and polishing belts of the endless type.

In quantity production buffing and polishing operations of the kind in which work pieces are conveyed past buffing machines, it has been found that a single endless type buffing belt can produce a finish on the work pieces equivalent to that of several buffing wheels. This is due to the fact that to achieve the desired finish, the work piece must be maintained in contact with the buffing wheel for a predetermined interval as it proceeds down a conveyor at some fixed speed. If one wheel cannot complete the finish in the allotted time, then several may have to be spaced along the conveyor. With a belt, the belt length can be varied to afford the required contact time. Furthermore, a belt usually only requires one machine while, generally, a separate machine is necessary for driving each buffing wheel. Consequently, by utilizing a belt fewer machines are needed with resultant savings not only in machines but also in floor space, maintenance and tooling. In exploiting these advantages, the problem is to develop an endless buffing belt that is superior or at least comparable to a buffing wheel in durability, cost and efficiency.

With the foregoing considerations in mind, the invention seeks to provide a buffing and polishing belt of the endless type that is easily constructed at a minimum cost, that is adaptable to a variety of operations, that is durable, and that is efficient in operation, especially in polishing and buffing irregular surfaces.

By the invention, there is proposed a method of making an endless buffing belt by advantageously arranging and attaching a plurality of multiple thickness buffing fingers to a belt member.

Further, the invention contemplates a method of making an endless buffing belt by fastening a row of bound multiple layer pads to the belt proper and positioning and securing the pad ends in an upstanding position relative to the belt proper to afford an effective buffing and polishing surface.

More specifically, the invention provides a method of making an endless belt by forming a plurality of buffing fingers for installation on the belt from a series of multiple ply pads progressively developed from appropriate buffing and polishing material.

In carrying out the invention, an endless buffing belt is made, first, by stacking a series of sheets of suitable buffing and polishing material cut to a predetermined shape. These sheets are folded one or more times parallel to one edge forming relatively thick pads which then are laterally spaced adjacent to each other and bound together in a row. Next, one or more rows of these pads are fastened to an endless belt member with each row extending parallel to the belt. Finally, to afford a plurality of buffing fingers, the pads are folded so that the ends are in an upstanding position relative to the belt member and secured in place.

2

The foregoing and other objects and advantages will be apparent from the following description and from the accompanying drawings, in which:

Figure 1 is a perspective view of a stack of sheets cut from a piece of suitable buffing and polishing material;

Figure 2 is a perspective view demonstrating a mode of creating multiple layer pads by folding the Figure 1 stack;

Figure 3 is a perspective view of a group of folded pads aligned in a row;

Figure 4 is a perspective view of the pads bound together;

Figure 5 is a fragmentary perspective view of a section of a belt after several rows of bound pads have been fastened thereto and the pads folded in place to furnish a plurality of buffing and polishing fingers;

Figure 6 is a fragmentary plan view illustrating a staggered arrangement of the fingers on the belt;

Figure 7 is a fragmentary side view of the belt depicting the fingers secured in a standing position relative to the belt; and

Figure 8 is a side view of a buffing machine utilizing a buffing belt constructed according to the invention.

Referring to Figure 1, 10 designates a multiple layer 25 or ply sheet formed by stacking and aligning a series of pieces 12 one on top of the other. The pieces 12 are cut to some predetermined size and shape from a larger piece of cloth fabric or other suitable buffing and polishing material. A three ply sheet is depicted; however, the 30 number of layers may be varied as well as the size according to the requirements of a particular buffing operation.

As best shown in Figure 2, the sheet 10 is double folded along the dotted lines 14 so that the edges 16 thereof are substantially parallel. This step furnishes a relatively 35 thick pad 18, the thickness of which can easily be varied by the number of folds. Furthermore, by this folding operation the pad can have a relatively elongated configuration with all of the several layers maintained in alignment. Otherwise, numerous pre-cut narrow strips 40 would have to be properly stacked to provide the necessary thickness, constituting a time consuming operation. In addition, the many more exposed edges would increase the edge fraying problem.

Several of these pads 18 are laterally spaced adjacent 45 to each other in a row, as viewed in Figure 3, and then bound together. Preferably, a binder strip 20 is positioned along the mid portion of the spaced pads 18 extending transverse to the major axes of the pads and sewed or otherwise fastened thereto. This operation affords a one- 50 piece structure which is easily manageable during preparation for the next step.

In the next step, with reference to Figures 5 and 6, one or more continuous rows of the bound pads 18 are 55 positioned on the exterior surface of an endless belt member 22 with the binder strip 20 extending parallel to the belt member 22 and then suitably attached thereto as by sewing. Preferably, the rows are arranged so that the pads in each row will be staggered relative to the pads 60 in the adjacent rows (see Figure 6), hence providing a more effective buffing surface. After the bound pads 18 are secured in position, each pad is folded with the edges 24 substantially parallel and suitably secured, e.g., by double stitching at 26 along a line parallel to the belt 65 member 22 (see Figure 7) to produce plural sets of buffing and polishing fingers 28 extending from the belt member 22.

The position of the double stitching 26 can be varied to 70 increase the rigidity of the fingers 28; for instance, referring to Figure 5, if the double stitching 26 is moved downwardly towards the edges 24, the fingers 28 will

become more rigid with less tendency to deform when pressure is exerted at the edges 24.

In Figure 8, an endless buffing belt 30, constructed according to the foregoing method, is demonstrated installed on a buffing machine, designated generally at 32. As shown, the belt 30 is mounted on a driving pulley 34 and an idler pulley 36, with the latter pulley being adjustable inwardly and outwardly from the axis of the driving pulley 34 to vary the belt tension in a well known manner. A suitably mounted motor 38, through belts 40, drives the pulley 34 and, consequently, rotates the belt 30. Positioned below the belt 30 is a movable table 42 or other type conveying device by which work pieces are carried past the upstanding fingers 28 on the belt. As can be seen, the extent of the belt over the table 42 determines, along with the speed of the table, the interval that the work piece is in contact with the buffing fingers 28. If the belt were installed on a single wheel, this contact time would be considerably reduced, and if this period were not sufficient to produce the desired finish, one or more wheels would have to be employed.

During the construction of the belt 30, the various components have been depicted fastened by stitching although, as mentioned, other fastening means could be utilized. However, because the structure of the illustrated embodiment is especially suited for sewing operations, it is a desirable cost reducing feature, especially when compared with some mechanical fastening device. Furthermore, the width of the belt and the number of rows of fingers 28 can be varied, as well as the length of these fingers. Whether the fingers are staggered or otherwise arranged, of course, may be determined by the particular operation.

I claim:

1. The method of making buffing belts comprising folding a sheet of fabric material parallel to a first edge to provide a multiple ply pad, positioning a plurality of the pads next to each other in a line, fastening a binder strip to a middle portion of the pads with the binder strip extending parallel to the line of the pads to afford a bound row of pads, attaching the bound row of pads to an endless belt in a continuous line extending circumferentially of the belt and parallel to a circumferential edge thereof, and folding the pads to extend parallel with said circumferential edge to an upstanding position relative to the flat face of the belt to furnish a plurality of buffing fingers.

2. The method of making buffing belts as defined in claim 1 with the added step of fastening adjacent fingers of each folded pad together in the upstanding position at a distance from the face of the belt determined by the degree of flexibility desired in the fingers.

3. The method of making buffing belts comprising cutting fabric material into a series of pieces of uniform predetermined size, aligning a plurality of the pieces one on top of the other to provide a multiple layer sheet, folding the sheet parallel to a first edge to afford a multi-

ple ply pad, positioning a plurality of the pads next to each other in a line, fastening a binder strip to a middle portion of the pads with the binder strip extending parallel to the line of the pads to afford a bound row of pads, attaching the bound row of pads to an endless belt in a continuous line extending circumferentially of the belt and parallel to a circumferential edge thereof, and folding the pads to extend parallel with said circumferential edge to an upstanding position relative to the flat face of the belt to furnish a plurality of buffing fingers.

4. The method of making buffing belts comprising cutting fabric material into a series of pieces of uniform predetermined size, aligning a plurality of pieces one on top of the other to provide a multiple layer sheet, folding the sheet a plurality of times parallel to a first edge to furnish a multiple ply pad, positioning a plurality of the pads next to each other in a line, fastening a binder strip to a middle portion of the pads with the binder strip extending parallel to the line of the pads to afford a bound row of pads, attaching a plurality of the bound row of pads to an endless belt in a continuous line extending circumferentially of the belt and parallel to a circumferential edge thereof with the pads of each row in staggered relation to the pads in adjacent rows, and folding the pads to extend parallel with said circumferential edge to an upstanding position relative to the flat face of the belt to furnish a plurality of buffing fingers.

5. An endless buffing belt comprising an endless belt backing member, a series of binder strips and a plurality of sets of buffing fingers formed from medially folded multiple ply fabric material and bound together with the folded faces confronting each other by each binder strip to provide a plurality of rows of bound fingers, with each of the rows of bound fingers being attached to the belt backing member in a continuous line extending circumferentially of the belt and parallel to a circumferential edge thereof with the fingers in an upstanding position relative to the flat face of the belt to furnish a plurality of buffing fingers.

6. An endless buffing belt as defined in claim 5 wherein the bound fingers in one row are staggered relative to the bound fingers in adjacent rows.

7. An endless buffing belt as defined in claim 5 wherein the adjacent fingers of each folded pad are joined together in the upstanding position at a distance from the face of the belt determined by the degree of flexibility desired in the fingers.
